Notice of Allowance from the United States Patent and Trademark Office, dated Sep. 28, 2018, in U.S. Appl. No. 29/659,528.

Primary Examiner — Jonathan J Han(74) *Attorney, Agent, or Firm* — ArentFox Schiff LLP**(57) CLAIM**

The ornamental design for a shoe, as shown and described.

DESCRIPTION

FIG. 1 is front right perspective view of a shoe showing our new design according to an exemplary embodiment; FIG. 2 is front view of the design shown in FIG. 1; FIG. 3 is a rear view of the design shown in FIG. 1; FIG. 4 is a right side view of the design shown in FIG. 1; FIG. 5 is a left side view of the design shown in FIG. 1; FIG. 6 is a top view of the design shown in FIG. 1; and, FIG. 7 is a bottom view of the design shown in FIG. 1. The broken lines shown in the figures are included for the purpose of illustrating portions of the shoe that form no part of the claimed design.
